Primary Examiner — Jack Reickel*Assistant Examiner* — Sydney M Evans(74) Attorney, Agent, or Firm — LAVERY, DE BILLY, LLP; Gwendoline Bruneau(57) CLAIM

The ornamental design for a snow shovel as shown and described.

DESCRIPTION

FIG. 1 is a front perspective view of a snow shovel showing our new design;

FIG. 2 is a first side view thereof;

FIG. 3 is a second side view thereof;

FIG. 4 is a front view thereof;

FIG. 5 is a top view thereof;

FIG. 6 is a bottom view thereof; and,

FIG. 7 is a rear thereof.

The broken lines shown in the figures form no part of the claimed design.
